UNITED STATES PATENT OFFICE.

CHARLES T. SCHOEN, OF PHILADELPHIA, PENNSYLVANIA.

FOLLOWER-PLATE FOR DRAW-BARS.

SPECIFICATION forming part of Letters Patent No. 437,940, dated October 7, 1890.

Application filed July 16, 1890. Serial No. 358,946. (No model.)

To all whom it may concern:

Be it known that I, CHARLES T. SCHOEN, a citizen of the United States, residing at Philadelphia, in the county of Philadelphia and 5 State of Pennsylvania, have invented a certain new and useful Improvement in Follower-Plates for the Draw-Rigging of Railway-Cars, of which the following is a full, clear, and exact description.

10 In the construction of follower-plates for the draw-bar spring-pockets of railway-cars the follower-plates are formed from a piece of iron cut to the proper length and width, with a hole drilled or punched through the center 15 to permit the passage of the draw-bar pin. It is obvious that there is no necessity for the full thickness of metal beyond the points or point in the follower-plate where the spring takes a bearing, in so far as imparting strength 20 to the follower-plate is concerned. It is equally obvious that the center, being perforated, is the weaker part of the plate.

Now the object of my invention is to construct a follower-plate with a greater thickness 25 of metal where greater strength is required and less thickness of metal where the least resistance is met, and form the opening therein in the dies instead of by drilling or punching, as has heretofore been practiced.

30 In the accompanying drawings, illustrating my invention, in the several figures of which like parts are similarly designated, Figure 1 shows in plan, side, and edge view the blank; and Fig. 2 shows in plan, side, and edge view 35 my follower-plate constructed from such blank. Fig. 3 is a plan view of the dies. Fig. 4 is a longitudinal section of the dies, taken in the plane of line A B, Fig. 3; and Fig. 5 is a vertical cross-section of the dies, taken in the 40 plane of line C D, Fig. 3.

The back of the follower-plate is flat, while the face has a central elevation around the pin-hole, and thence tapers to its ends, and accordingly I provide a male die or plunger a 45 having a projection or tongue b. This male die will form the back of the follower. The female die c has a cavity c' corresponding in

shape to the face of the follower-plate, and is also provided with a tongue or projection d rising vertically through the said die. In order to operate the tongue or projection d, I 50 bevel its lower end d', and arrange for co-operation with such beveled end a wedge-block e, which, by means of the pin e', is connected with a lever f secured to the die by a 55 post or fulcrum pin g.

The dies will be arranged in any suitable press, as usual.

A flat rectangular blank h is taken and heated and placed in the female die, and then 60 power is applied to bring the dies together, and as the metal flows under the pressure of the dies and in accordance with the shape of the said dies the said blank will be spread to form the flat back h' and central elevation h², 65 which receives the spring, and the sides h³ h³, which engage the guide-plates of the spring-pocket. At the same time, by the co-operation 70 of the tongues or projections b and d, the central hole h⁴ will be formed complete, with the exception of a thin web intervening 75 between the two tongues or projections b and d, which web may afterward be punched or cut out in any suitable manner. By this operation I form a follower-plate very perfectly and very expeditiously, with the metal distributed in accordance with the resistance 80 the plate is to bear in usage.

The dies described themselves may be used for punching or cutting out the web or fin in 80 the hole h⁴ in the following manner: When the follower-plate has been formed in the die, the wedge e is withdrawn, and what may be termed a "dummy-pin" is inserted in the hole formed by the upper die. After inserting this pin pressure is applied again and the pin or tongue in the upper die pushes the lower pin or tongue out of the way, thus cutting out the fin or web and leaving a clear 85 straight hole.

90 What I claim is—

1. A follower-plate for the spring-pockets of the draft-rigging for railway-cars, consisting of a central thick elevated portion to re-

ceive the spring and containing the pin-hole, and the reduced sides adjacent to said central elevation, substantially as described.

2. A follower-plate for the spring-pockets of the draw-rigging of railway-cars, having a central thickened portion containing the seat for the spring and the pin-hole, and reduced sides for engaging the guide-plates and forged in dies, substantially as described.

In testimony whereof I have hereunto set my hand this 14th day of July, A. D. 1890.

CHARLES T. SCHOEN.
